John Ellis

ATTORNEY

UNITED STATES PATENT OFFICE

PAUL HAUENSTEIN, OF BUFFALO, NEW YORK

LAMP SHADE

Application filed August 1, 1929. Serial No. 382,635.

It is well known to those skilled in the art that in the type of lamp shades used to shield one side of an electric bulb, it is necessary to make the shade considerably longer than the bulb used, in order that there may be sufficient space for the bulb when it is being screwed into place, with the result that such shades are cumbersome and awkward, as well as resulting in a waste of material in their manufacture.

It has been an object of my invention to provide a shade which shall conform substantially to the shape of that portion of the electric bulb which it shields, whereby there is no waste space or material in the shade.

Another object has been to provide a shade which shall be inexpensive to manufacture and easy to assemble.

Moreover, my shade is easily detached, thus making the replacement of the bulb an easy matter.

Furthermore, it is possible to form the shade so that it more nearly approaches the efficiency derived from a parabolic reflector, thus giving greater concentration of the reflected rays. As a result of such formation the shade is very compact and occupies minimum space.

Moreover, it has been an object to provide means for securing the shade in place which shall make it easily detachable at the same time, and also obviating the use of any mechanical screws, which are very objectionable in shades of this type.

The above objects and advantages have been accomplished by the device shown in the accompanying drawings, of which:

Fig. 1 is a side elevation showing my shade in position.

Fig. 2 is an enlarged, transverse, sectional view, taken on line 2—2 of Fig. 1.

Fig. 3 is a face view of the shade.

My device comprises a disc 5 to which the shade 6 is secured, and this disc is preferably held in place upon the lamp socket 7 by

flanges 8 and 9 formed on the socket and arranged one at each side of the disc. The disc is thus mounted so that it may be rotated if desired. The disc is provided preferably on its upper portion with a perimeter formed substantially circularly in shape and extending from the top to a point slightly below the center thereof. The circular surface 10 of the upper perimeter terminates at each side in an inwardly curved surface 11 which ends in a shoulder 12 formed by a reduced circular perimeter 13 at the bottom of the disc.

The shade 6 follows substantially the general contour of that portion of the lamp bulb 14 which it shields, and it is provided with a neck portion 15. This neck portion is formed with a U-shaped semi-circular groove 16 extending from one edge 17 of the shade to the other. At each of the edges 17 the groove is provided with a lip 18. The U-shaped groove 16 engages with the upper circular surface 10 of the disc 5, and the lips 18 are designed to engage the shoulders 12, when the shade is in place. The shade is made preferably of a metal stamping and it will have sufficient resiliency so as to cause the lips to snap in underneath and in engagement with the shoulders 12 when the shade is forced into position. Obviously, when it is desired to remove the shade, it is only necessary to force one of the lips out of engagement with the shoulder 12 whereupon the shade may be easily removed from the disc.

Obviously, some modifications of the details herein shown and described may be made without departing from the spirit of my invention or the scope of the appended claim, and I do not, therefore, wish to be limited to the exact embodiment herein shown and described, the form shown being merely a preferred embodiment thereof.

Having thus described my invention, what I claim is:

The combination with a lamp socket, of a lamp shade comprising a disc carried by the

socket and disposed in a plane at right angles to the axis of the socket, the disc being provided with oppositely arranged shoulders, a shade member formed with a groove in its neck portion and with a lip at each end of the groove for engagement with the shoulders of the disc to hold the shade member in place upon the disc.

In testimony whereof, I have hereunto set my hand.

PAUL HAUENSTEIN.
